(57) **CLAIM**

The ornamental design for a tray, as shown and described.

DESCRIPTION

FIG. 1 is a top, front perspective view of a tray in accordance with a first embodiment of our new design;

FIG. 2 is a bottom, rear perspective view thereof;

FIG. 3 is a top plan view thereof;

FIG. 4 is a bottom plan view thereof;

FIG. 5 is a front elevation view thereof;

FIG. 6 is a rear elevation view thereof;

FIG. 7 is a left side elevation view thereof;

FIG. 8 is a right side elevation view thereof;

FIG. 9 is a top, front perspective view of a tray in accordance with a second embodiment of our new design;

FIG. 10 is a bottom, rear perspective view thereof;

FIG. 11 is a top plan view thereof;

FIG. 12 is a bottom plan view thereof;

FIG. 13 is a front elevation view thereof;

FIG. 14 is a rear elevation view thereof;

FIG. 15 is a left side elevation view thereof; and,

FIG. 16 is a right side elevation view thereof.

The dash-dot lines in FIGS. 9-14 define the bounds of the claimed design. The claimed design extends to but does not include the defined boundary.

The claim is shown with a symbolic break in its length. The appearance of any portion of the article between the break lines forms no part of the claimed design.

1 Claim, 10 Drawing Sheets
